UNITED STATES PATENT OFFICE.

HENRY SCHLACHTER, OF BEATRICE, NEBRASKA, ASSIGNOR TO DEMPSTER MILL MANUFACTURING COMPANY, OF BEATRICE, NEBRASKA, A CORPORATION OF NEBRASKA.

DOUBLE-STROKE WORKING HEAD.

Application filed May 18, 1926. Serial No. 109,948.

This invention relates to double stroke working heads for the operation of the several pump rods of multiplunger cylinders such as are sometimes used in deep well pumps; and the objects and nature of the invention will be readily understood by those skilled in the art in the light of the following explanations of the accompanying drawings that illustrate what is now believed to be the preferred mechanical expression of the invention from among other forms and arrangements within the spirit and scope thereof.

An object of the invention is to provide an improved working head for actuating several pump rods, that will be durable, efficient and quiet in operation by reason of lubrication and enclosing possibilities due to the construction and arrangement of the parts, and that will be economical in construction and assembly.

With this and other objects in view, the invention consists in certain novel features in construction and combination and in arrangement of parts and features as more fully and particularly set forth and specified hereinafter.

Referring to the accompanying drawings forming a part hereof:

Fig. 1 shows the working head of my invention in side elevation, the top cover hood appearing in vertical section.

Fig. 2 is an end elevation, the cover hood appearing in vertical section.

Fig. 3 is a vertical section taken in a plane at right angles to the axis of the drive shaft.

Fig. 4 is a top plan, the cover hood appearing in horizontal section.

Fig. 5 is a detail vertical section taken in a plane parallel to the axis of the drive shaft.

Fig. 6 is a horizontal section on the line 6-6, Fig. 3.

Fig. 7 is a horizontal section on the line 7-7, Fig. 3.

Fig. 8 shows a modified structure in vertical section.

Fig. 9 is a detail vertical section of the structure of Fig. 8 taken in a plane parallel with the drive shaft.

Fig. 10 shows the structure of Fig. 8 in top plan.

Fig. 11 shows the structure of Fig. 8 in horizontal section.

Referring to the construction of Figs. 1-7, of the drawings, the main supporting frame or structure (which is mounted and supported by any suitable means, not shown) embodies a strong rigid open-top lubricant retaining gear case 1, on which is mounted a superstructure or elevated supporting frame, made up of a pair of approximately-similar castings or other strong rigid frame members, each consisting of a horizontal cross bar 2, formed with end legs 2^a, that diverge downwardly. These two frame members are arranged side by side with the lower ends of their legs 2^a, seated on and bolted or otherwise clamped or fixed to the opposite side top flanges or edges of the gear case 1. The elevated horizontal cross bars or heads 2, are parallel and secured together in relatively fixed relation by cross bolts 2^b, or in any other suitable manner, and said bars 2 are so relatively formed or arranged as to provide between their adjacent vertical side faces a vertical space for the passage and reciprocation of certain operating members connected with or forming upright extensions of the pump rods.

This superstructure frame consisting of cross heads 2 and their supporting legs, also supports and provides for anchoring a pair of spaced parallel rigid upstanding guide rods 3, at their lower ends clamped or otherwise fixed to the heads 2 and arranged at the outer edges thereof, and at their upper ends these guide rods are fixed to and rigidly connected by cross head 3^a.

These guide rods are braced and stiffened by spaced parallel inclined side brace rods 3^b, at their upper ends bolted or otherwise fixed to the opposite end portions of the cross head 3^a, at one side thereof, and at their lower ends bolted or otherwise fixed to the heads 2, at corresponding ends thereof.

The rotary main drive shaft 4, is carried by, extends horizontally through and to the exterior of the gear box, and is mounted in suitable bearings carried by vertical walls of said box. In the particular example shown, the drive shaft 4 is located at the top portion of one side or end of the box. The end portions of said shaft within the box provide two identical geared pinions 4^a, that are in constant driving mesh with the teeth of two relatively large vertically rotating parallel identical gear wheels 5, suitably mounted and supported by and within the

gear box. In one form of my invention, these two gears 5, are fixed to the opposite ends of a common rotary horizontal shaft or axis 5^a. This shaft 5^a, is carried by and mounted in a journal box arranged approximately centrally within the gear case, and fixed thereto. This journal box consists of a pillow 6, fixed to and centrally traversing the upper part of a central vertical well or curb 1^a, within and rising from the bottom of the gear case 1, and a cap 6^a. In the example shown, the pillow and cap have longitudinal horizontal side flanges through which bolts pass to clamp the cap to the pillow, the side flanges being recessed or otherwise formed, to permit free vertical passage of vertical reciprocating pump rod operating parts through the well 1^a, and at opposite side of the journal box. The well and journal box are arranged in the gear case between the two vertical rotary gear wheels 5.

The shaft 5^a, is preferably formed with opposite end projecting vertical concentric annular flanges 5^b, beyond the ends of the journal box. The innd vertical side faces of the webs of the gear wheels 5 fit the outer vertical faces of the shaft ends and flanges and are secured thereto by clamping bolts 5^c.

The pump rod actuating means driven by the gear wheels 5, comprises a vertically-reciprocating cross head slide 7, that extends horizontally between the vertical guide rods 3 and embodies vertical parallel end sleeves 7^a confined to and slidable longitudinally of said rods 3, and identical pitmen 8, at their upper ends pivotally joined to said slide to actuate the same and at their lower ends eccentrically joined to the gears 5, to be actuated thereby to reciprocate said slide.

The gear wheels 5 are provided with diametrically opposite outwardly projecting crank pins 5^d, on which the lower ends of the pitmen 8 are mounted and confined.

At their upper ends the pitmen 8, are pivotally joined to the slide 7, in any suitable manner, although the upper ends of the two pitmen 8, are preferably joined by a cross rock shaft 8^a, to the opposite ends of which the upper ends of the pitmen are secured, and this rock shaft 8^a, is journaled and confined in a bearing extending longitudinally through a front side extension 7^b, of the slide 7.

The pitmen are arranged beyond the ends of the reciprocating slide, and beyond opposite sides of the superstructure frame 2, 2^a, and beyond the outer side faces of the gear wheels 5, and extend into the gear case 1, between the vertical end walls thereof and the gear wheels 5.

And the arrangement is such that the vertical planes in which the pitmen operate are beyond the guide rods 3 and braces 3^b, so

that said rods and braces are between said planes. Also, the vertical plane in which the guide rods 3, are arranged is to one side of the vertical plane in which the axis 5^a, of the gear wheels 5, and the axis 8^a, coupling the pitmen 8, are arranged. The front side extension 7^b, of the slide 7, is preferably so arranged as to locate the rock shaft 8^a, parallel with and in the same vertical plane as the axis 5^a, of gear wheels 5.

In the particular example shown, two parallel depending oppositely reciprocating pump rods 9, 10, appear, the rod 10, being tubular, with the other rod 9, extending therethrough and working therein.

To the upper end of tubular rod 10, is fixed a horizontal cross head 10^a, below the gear case 1, and a pair of spaced parallel vertical pump rod extensions 10^b, are fixed to and rise from the cross head 10^a, and, at points a distance above the gear case 1, are provided with straight parallel geared racks 10^c, in upward continuation of the rods 10^b, and fixedly secured thereto.

The center rod 9, is provided with a vertical double rack 9^a, rigid therewith and forming a longitudinally aligned upward extension thereof, and located midway between the two racks 10^c. The center double rack 9^a, can be coupled to rod 9, in any suitable manner or by any suitable means, although I show a yoke connection between the rod and rack to avoid the journal box 6, 6^a, that carries the shaft of gear wheels 5, by straddling the same. This yoke connection embodies a cross head 9^b, fixed to the rod 9, and located below the journal box, a cross head 9^c, above the journal box and rigid with the lower end of double rack 9^a, and spaced vertical stiff tie rods 9^d, arranged beyond opposite sides of the journal box and secured to and connecting ends of the cross heads 9^b, 9^c, to form a stiff push and pull connection between rod 9 and rack 9^a.

The straight rack 9^a, is secured at its upper end to the reciprocating cross head 7, preferably by screw threaded connection between the reduced threaded upper end of the rack and threaded nipple 7^d, depending from and rigid with the front extension 7^b, of the crosshead and located midway between the pitmen 8 and in the vertical plane of the shafts 8^a, 5^a.

Operative driving connection is established in any suitable manner between the rack 9^a, and the racks 10^c of the pump rod extensions 10^b. For instance, I show the double rack 9^a, arranged between and in constant driving mesh with a pair of pinions 11, which are also in constant driving mesh with the single racks 10^c, respectively. By this arrangement, upward movement of double rack 9^a, will, through the medium of rotary pinions 11, cause corresponding downward movement of both racks 10^c, and down-

ward movement of rack 9^a, will cause upward movement of racks 10^c, and hence simultaneous opposite reciprocation of pump rods 9, 10.

5 The operating and controlling connections of the pump rods 9, 10, extend upwardly through the gear case between the large gears 5 and at opposite sides of the journal box, 6, 6^a, and upwardly from the gear box through 10 the vertical space between the frame superstructure parts 2, 2, to points above the same.

The floor or bottom of the gear case provides a horizontally elongated narrow vertical opening for the free passage of said connections. 15 The gear case is cast or otherwise formed with the internal annular upstanding flange or well curb 1^a, surrounding said opening and rising therefrom to carry the journal box 6, 6^a, and to enable the gear case to receive and retain, at least to the level of the top edge of said well or curb, a large or deep body of lubricant. Suitable supporting and mounting means for the pinions 11, providing confining guides for the racks 9^a, 10^c, 20 are mounted on the superstructure frame members 2, 2.

For instance, I show a pair of parallel spaced horizontal bars, such as angle bars 12, arranged on and longitudinally of and 30 bolted to the frame members 2, with the pinions arranged between the adjoining vertical faces of said bars and rotatable on and carried by short horizontal parallel shafts or spindles 13 carried by and extending transversely through said bars. The inner vertical faces of the bars serve to guide and confine the racks.

The bars 12, can also carry suitable means to bear against the smooth outer longitudinal 40 edge portions of racks 10^c, to maintain the gearing of said racks in constant mesh with pinions 11. For instance, I show vertically arranged guide or bearing blocks or shoes 14, adjustably arranged and supported between the outer ends of the bars and bearing 45 against the outer longitudinal edges of said racks. These shoes 14 are normally clamped to the bars by bolts, but can be loosened and adjusted to take up wear or for other reasons by adjustable stop bolts 14^a. In practice, the usual cover, preferably an open-bottom 50 upstanding removable sheet metal hood 15, is employed to rise from the gear case and cover the open-top thereof and enclose all 55 of the fixed and working parts rising from or extending above the gear case, and thereby protect the same and the interior of the gear case from dirt and the weather and to prevent escape of lubricant. This hood is preferably 60 oil or lubricant tight, and at its annular lower edge fits on and is secured to the annular top edge or flange of the gear case 1, preferably to form a lubricant tight joint.

In operation, rotation of the drive shaft 4, causes simultaneous rotation of the two large crank wheels 5, which operate as one gear, and through the medium of the two pitmen 8, which operate as one, the cross head slide 7, is reciprocated 65 longitudinally of rods 3. The rack 9^a, secured to and depending from the slide reciprocates with said slide, and rotates the pinions 11, and thereby simultaneously reciprocates the racks 10^c in the opposite direction from that in which rack 9^a is moving.

In the modification shown by Figs. 8, 9, 10, and 11, the supporting frame or structure embodies a lubricant gear case or box that is approximately closed at the top, and comprises the open top bottom section 16, and the open bottom section 17, the annular edges of said sections, around said open top and bottom meeting, and the sections are there bolted together to form a 80 preferably liquid tight joint.

The bottom of the lubricant retaining gear case is formed with a vertical opening for the passage of the pump rods 18, 19, and this opening is surrounded by an annular 90 flange or well curb 20, rising within the gear case to retain the lubricant therein.

The two pump rods 19 are connected together to operate as one, and usually formed upward extensions of a tubular rod through 95 which the center pump rod 18 extends. A double rack 18^a, forms a rigid upward longitudinal continuation of pump rod 18, and this rack is hung from and at its upper end secured to a lateral projection or extension of vertically reciprocatory cross head slide 21, confined to and vertically slidable on the fixed guide rods 22. These rods 22 are secured to and rise from the gear case and are secured together at their upper ends and stiffened by brace rods 23.

The twin pump rod extensions 19 are provided with single racks 19^a, forming upward extensions thereof, and these racks are held by backing rollers 24, in constant driving mesh with spur gear pinions 25, that are also in constant operative mesh with the double rack 18^a, so that the operation is as hereinbefore described with respect to the structure of Figs. 1-7.

The racks 18^a, 19^a, extend up through a vertical opening in the top of the gear case, and therefrom between a pair of parallel spaced bars 26, secured on the top of the gear case and bridging said opening. The rolls 24, and pinions 25, are arranged between these bars and are carried by spindles or axes extending transversely through the parts.

The twin reciprocating pitmen 27, that reciprocate slide 21, extend from the gear or crank wheels 28 in the lower section of the gear case, upwardly through the opening in

the gear case top, to the side extension of the slide, and are secured to the opposite ends of a rock shaft 29, mounted and journaled in said extension. The large vertical twin gears or crank wheels 28, operate as one wheel, although arranged at opposite sides or ends of the gear case interior, and independently mounted on separate alined concentric trunions 30, carried by and projecting inwardly from the opposite end walls of the lower section 16, of the gear case. The twin crank wheels 28, are simultaneously driven in the same direction by twin pinions 31, on a common rotary drive shaft 31^a, extending across the interior of the gear case and extending to the exterior thereof and mounted in bearings carried by the walls of gear case section 16.

The pitmen 27, extend down through the interior of the gear case between the crank wheels 28, and beyond opposite sides of the pump rods, racks, and well 20, and at their lower ends have crank pin connection with said wheels 28, so that the operation is as hereinbefore explained with respect to the structure first described.

In practice, the usual lubricant tight sheet metal hood, not shown, is placed over the fixed and working parts that extend above the gear case, and is removably secured on the gear case to cover the top thereof and form a lubricant tight joint therewith and a lubricant cover.

The constructions described are rugged in structure and exceedingly durable, and are simple to construct and assemble and provide for long-time self lubrication and enclosure to prevent lubricant waste and to exclude the weather and dust and dirt.

Material advantages in the matters of economy, dependability, durability, low production and upkeep costs, and efficiency in operation are attained, with the advantages of a weather proof lubricant tight encasement, and the advantageous cooperation of crank and pinion drive for oppositely reciprocatory pump rods, with crank wheel, pitman and reciprocatory slide actuating means.

It is evident that various changes, modifications, and variations might be resorted to without departing from the spirit and scope of the invention and hence I do not wish to limit the invention to the approximately exact disclosures hereof:

What I claim is:

1. In combination, in a double stroke working head, pump rods, a supporting gear case, a twin crank wheels mounted in said case, an elevated vertically reciprocatory cross head, twin pitmen for reciprocating said elevated cross head from said wheels, and rack and pinion means connecting the pump rods for simultaneously and oppositely reciprocating the pump rods, said rack and

pinion means being coupled to and actuated by said cross head.

2. In combination, in a working head for a multi-piston pump, oppositely reciprocatory pump rods provided with racks in upward longitudinal continuation thereof and with means connecting said racks to cause simultaneous opposite reciprocation thereof and the pump rods depending therefrom, a gear case into which said rods extend and from which said racks extend upwardly, a vertically reciprocatory slide arranged above said gear case and coupled to the upper end of one of said racks to vertically reciprocate the same, a crank wheel mounted in said gear case, and a pitman operatively coupled thereto and extending upwardly from said gear case and operatively coupled to said slide.

3. In combination, a supporting gear case, a fixed vertical slideway rising from said case and carried thereby, a vertically reciprocatory slide above said gear case and confined to said slideway, a vertically reciprocatory pump rod at its upper end coupled to said slide and depending through said gear case and vertically reciprocated by said slide, another vertical reciprocatory pump rod depending through said gear case, operating connections from said first mentioned rod to said second mentioned rod to simultaneously and oppositely reciprocate the second rod from the first rod, and eccentric means for reciprocating said slide, arranged within the gear case and extending upwardly therefrom to said slide and operatively coupled thereto.

4. A working head for actuating oppositely reciprocatory pump pistons, comprising a gear case, a drive shaft therein, twin crank wheels therein driven by said shaft, vertical reciprocatory pump rods extending through said case from a point below to a point above said case and arranged between said wheels, a vertically reciprocatory slide arranged above said gear case and provided with a slideway supported by and rising from said case, pitmen actuated by said wheels and rising from said case and coupled to said slide to reciprocate the same, one of said rods operatively coupled to and reciprocated by said slide, and rack and pinion means operatively joining said rods.

5. A working head for actuating oppositely reciprocatory pump pistons, comprising a gear case, vertical guide rods fixed to said case and rising therefrom, a vertically reciprocatory slide above said gear case and confined to said rods, oppositely reciprocatory pump rods extending downwardly through said case, one of said rods having its upper end directly coupled to said slide, the upper portions of said rods having longitudinal racks extending above said case and geared together to cause simultaneous

opposite reciprocation, and rotary driving means within said case and having operative connection with said slide above the case to reciprocate the slide.

5 6. In combination, a gear case, a fixed frame above said case, pinions mounted in said frame, a center pump rod extending through said case and having a double rack forming the upper part thereof and guided by said frame and in mesh with said pinions, side pump rods extending through said case and having racks forming the upper parts thereof and in mesh with said pinions and guided by said frame, a vertically reciprocatory slide arranged above said gear case and frame and directly coupled to the upper end of one of said rods to reciprocate the same and the other rods, and rotary operating means arranged within the gear case 20 having eccentric operating connection with said slide to reciprocate the same.

7. In combination, a gear case, twin crank wheels therein, a drive shaft therefor, a vertical slideway fixed to said case, a vertically reciprocatory slide confined to said slideway, pitmen from said wheels to said slide to reciprocate the same, a center vertical pump rod coupled to said slide and vertically reciprocated thereby, another vertical pump 30 rod, and rack and pinion gearing connecting said pump rods to simultaneously and oppositely reciprocate the second rod from the first rod.

8. In combination, a gear case, vertical fixed guide rods carried by said case, a vertically reciprocatory cross head slide confined to said rods and formed with a transverse tubular bearing, a transverse rock shaft in said bearing, crank wheels in said 40 case, pitmen actuated by said crank wheels and extending upwardly and at their upper ends coupled to said shaft to reciprocate said slide, oppositely reciprocatory pump rods, and pinion and rack transmission means operatively connecting said rods to cause simultaneous and opposite reciprocation, one of said rods being directly coupled to said slide and reciprocated thereby.

9. A working head for multi-piston pumps, comprising, in combination, a supporting gear case having a top opening and a bottom opening, several reciprocatory pump rods extending down through said case from a point above the same to a point 50 below the same, a power transmission operatively connecting said rods above said case to cause simultaneous opposite reciprocation thereof, a rotary drive shaft within said case, a rotary member within said case and driven by said shaft, and operative connections actuated by said member for reciprocating said rods and coupled to the upper end of one of said rods above said case and embodying guiding means above and carried 55 by the case and a pitman extending up-

wardly from said member to a point above said case.

10. A working head for multi-piston pumps, comprising, in combination, a supporting encasement arranged to contain lubricant, a drive shaft, a rotary member driven thereby, several reciprocatory pump rods, operative connections between said rods to reciprocate same simultaneously in opposite directions, suitable crank and reciprocating cross head connections between one of said rods and said member to reciprocate said rod and arranged to convert rotary motion into reciprocatory movement and means for retaining said rod in vertical alignment during reciprocation, said connections being in part located exteriorly of and above said encasement.

11. A working head for multi-piston pumps, comprising in combination a supporting encasement arranged to contain lubricant, a drive shaft, a rotary member driven thereby, several reciprocatory pump rods, said encasement providing a vertically open well for the passage of said rods surrounded by a lubricant excluding curb operative connections between said rods to reciprocate same simultaneously in opposite directions, suitable connections between one of said rods and said member arranged to convert rotary motion into reciprocatory movement and means for retaining said rod in vertical alignment during reciprocation.

12. A working head for multi-piston pumps, comprising in combination, a supporting encasement arranged to contain lubricant, a drive shaft, a rotary member driven thereby, several reciprocatory pump rods with suitable intervening connecting gear mechanism to cause their simultaneous 100 opposite reciprocation under the operating power of one of the rods, operative connections between one of said rods and said member to reciprocate said rod and guiding means for said connections, said connections extending upwardly from said member to said rod and arranged to convert rotary motion into reciprocatory movement.

13. In combination, a lubricant containing encasement, a fixed frame above said encasement with pinions mounted therein, a center pump rod extending through said encasement and having a double rack forming the upper part thereof and guided by said frame and in mesh with said pinions, side pump rods extending through said case and having racks forming the upper parts thereof, and in mesh with said pinions and guided by said frame, a vertically reciprocatory slide arranged above said gear case 115 and frame and directly coupled to the upper end of one of said rods to reciprocate the same and the other rods, rotary operating means arranged within the encasement having eccentric operating connection extend- 120 125 130

ing up to said slide to reciprocate the same, and a weatherproof, oil retaining hood to cover said mechanism and encasement.

14. A pump working head comprising several vertically reciprocatory rods connected together to simultaneously reciprocate in opposite directions, in combination with a vertically reciprocatory slide operatively connected to said rods to drive the same, a rotary driving member operatively connected to said slide to reciprocate the same, a supporting base for said head embodying a lubricant retaining gear case in which said rotary member is mounted to travel in the lubricant, said case having a well extending vertically therethrough and formed by a vertical lubricant retaining curb, said case being open at the top, an open frame fixed to and rising from said case to a point above its open top, said rods extending into said frame and through said case and the well therein, a vertical slideway carried by said frame, said slide being confined to said slideway and elevated above said casing, and a removable hood open at its bottom and covering and rising from said case and enclosing said frame, slideway, slide and other parts above said case.

15. A pump working head comprising a vertically reciprocatory slide, a fixed vertical slideway therefor, a rotary driving member, and eccentric driving connection therefrom to said slide to reciprocate the same, in combination with several vertically reciprocatory upright rods, gearing connecting said rods to cause opposite reciprocation thereof, at least one of said rods coupled to said slide for driving the rods, a gear case forming a lubricant receptacle and having an open top through which the operating parts within the case are accessible, said rotary driving member being arranged within the case to operate in the lubricant therein, said rods extending through the case from below to above the same, said slideway being arranged above the open top of the case with said slide confined to said slideway, and a removable cover hood rising from the case and covering its open top and enclosing and protecting said rods, the slideway, the slide and other parts above said case.

16. A working head for a pump comprising a gear case having a well opening through the bottom thereof and formed with a vertical annular curb, whereby the case forms a lubricant receptacle, a rotary driving member mounted in said case to work in the lubricant, fixed slide rods carried by and arranged above said case, a vertically reciprocatory cross head slide above the case and confined to said slide rods, a slide actuating pitman extending from said rotary member upwardly to said slide, several vertically reciprocatory rods extending through said case

and the well therein to a point above the same, one of said reciprocatory rods coupled to said slide for actuating the rods, rack and pinion gearing above the case and connecting said rods to cause opposite reciprocation, and a removable cover hood for and mounted on said case and protecting and enclosing all of said parts above the case.

17. In a pump working head, in combination, a supporting base embodying a gear case having an open bottom well surrounded by an annular vertical curb whereby the case forms a lubricant retaining receptacle, twin crank wheels in said case beside said well to work in the lubricant, a drive shaft in the case for said wheels, a vertically-reciprocatory slide and its guiding means above said case, twin pitmen extending from said slide downwardly into said case exteriorly of said well and actuated by said wheels, several reciprocatory pump rods extending upwardly through said well and the case to a point above the case and driven by said slide, and means above the case operatively connecting said rods to reciprocate in unison in opposite directions.

18. In a pump working head, in combination, a supporting gear case open at the top and forming a lubricant retaining receptacle, whereby operating parts within the case are accessible through its open top, a removable weather-excluding lubricant-retaining hood rising from and carried by said case and forming a top cover therefor, said hood open at its bottom and fitting the top of the case around its open top, several reciprocatory rods extending upwardly through said case from below and into said hood, and means for driving said rods in unison in opposite directions, said means protected by said hood, and accessible when the hood is removed, and comprising a rotary driving member in said case, a reciprocatory slide, and operating connection from the member to the slide, said hood being vertically removable from and applicable to said case as a unit.

19. In a pump working head, in combination, a supporting gear case forming a lubricant retaining receptacle and having an internal open top and bottom well surrounded by an annular vertical curb, rising in said receptacle to an elevation above the lubricant level, a transverse journal box carried by said curb, a shaft mounted in said box and at its ends provided with crank wheels at the exterior of said well to work in the lubricant in said case, a vertical slideway carried by the case and arranged above the same, a vertically reciprocatory slide confined to said slideway, twin pitmen for actuating said slide and extending down into said case at the outer sides of said wheels and actuated thereby, and a pump rod ex-

tending upwardly through said well and the case and operatively coupled to said slide.

20. In a pump working head, in combination, a supporting gear case forming a lubricant retaining receptacle and having an internal open bottom well surrounded by an annular vertical curb, a transverse journal box carried by said curb, a shaft mounted 10 in said box and at its ends provided with crank wheels at the exterior of said well to work in the lubricant in said case, a vertical slideway carried by the case and arranged above the same, a vertically reciprocatory 15 slide confined to said slideway, twin pitmen

for actuating said slide and extending down into said case at the outer sides of said wheels and actuated thereby, and several simultaneously oppositely reciprocatory pump rods extending through said well and the case, 20 at opposite sides of said journal box, one of said rods being offset around said box and coupled to said slide, means being provided to cause said rods when driven by said slide to reciprocate in unison in opposite directions. 25

Signed at Beatrice, Nebraska, this 13th day of May, 1926.

HENRY SCHLACHTER.
